(57) **CLAIM**

We claim the ornamental design for a plug for optic and electrical hybrid connector, as shown and described.

DESCRIPTION

FIG. 1 is a front perspective view of a plug for optic and electrical hybrid connector of the present invention;

FIG. 2 is another front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The outermost broken lines immediately adjacent to the full line showing of the claimed design represent the bounds of the claimed design while all other broken lines are directed to environment and are for illustrative purposes only; the broken lines form no part of the claimed design. In addition, the unshaded surface directly adjoining the top and bottom solid line edges in the FIGS. 1-3, 5, and 6 views form no part of the claimed design.
